PAPER ARTICLES OF APPAREL

Henry G. Hillard, Regina, Saskatchewan, Canada, assignor of fifty-one one-hundredths to Ira H. Bowman, trustee, and one-fifth to Ira H. Bowman, Regina, Saskatchewan, Canada

Application October 18, 1932. Serial No. 638,317

5 Claims. (Cl. 28—1)

The present invention relates to the employment of paper in the fabrication of articles of apparel; and, while not so limited in its scope, it is particularly adapted for and will be herein exemplified in connection with hat manufacture.

The utilization of paper in the manufacture of hats is not of itself new. Plaits or braids of flat or twisted paper of various kinds have been stitched together and reinforced by thread or flexible wire to form hat bodies, but by the very nature of the material and its treatment the production of soft, flexible hats as by knitting or crocheting has not been satisfactorily attained. The object of this invention is the production of a soft paper strand in a form capable of being successfully manipulated as a "yarn" by means of crochet or knitting needles and thereby fabricated into a homogeneous soft pliable resilient fabric in the form of a hat or similar article.

For a better understanding of the procedure involved, the several steps are graphically set forth by way of example in the accompanying drawing, wherein

25 Fig. 1 represents a strip of the paper stock; Fig. 2 a tube formed by curling the strip and securing the marginal edges;

Fig. 3 a tubular strand drawn into the fabric by a crochet hook or needle; and

30 Fig. 4 a fragment of the resultant fabric.

The strand of material lends itself to manipulation in crocheting, knitting and weaving machines and it will be understood that hand manipulation, as indicated in Fig. 3, is by way of illustration only.

As a starting material I employ a soft unglazed paper stock of no particular inherent strength such, for example, as semi-crepe paper as it comes from the mill, which has little resistance to deformation but a degree of elasticity or stretch, say from 3-10%.

The material is cut into strips 11, of $\frac{3}{4}$ to 1" in width, which are then folded transversely, the marginal edges being preferably secured together as by a suitable gum as at 12, resulting in tubular strands 13 of say $\frac{1}{4}$ " in diameter, preferably single ply and having no raw edges; which strands are transversely crushable and lend themselves like yarn to being manipulated by knitting or crochet needles to form the fabric 14 of a shaped hat which may be rolled or crushed into small compass and again restored to normal shape for wearing without deterioration or permanent set.

The size of the strand which depends upon the width of the paper strip will naturally be governed by the purpose to be served, whether the fabric is to be of coarse or fine texture.

By the gumming of its meeting edges, the tube is transversely sealed so that the trapping of air therein tends to give the strand "body" and "life", preventing total collapse or flattening while the strands are being inter-engaged and interlaced in the process of fabrication.

The construction of the strands and their interlaced relation is such as to render the article of apparel so made substantially weather-proof if not subjected to unreasonably rough handling when wet and it is easily dried without distortion or permanent injury. However, the material, preferably before fabrication, may be chemically treated by suitable well known weather-proofing substances whereby to render the same water-repellent, or the strands may be superficially

70 coated in such manner as not to impair the softness and flexibility of the same. By employing tinted paper any desired color of the finished article may be attained, and a silk-like lustre

75 may be imparted to the fabric by treatment of the strands with suitable known chemicals which will not impair the physical characteristics of the same.

80 The fabricated article, by reason of the material employed, the formation of the strand and the interlaced structure possesses a texture which is yielding, resilient, conformable, and readily deformable without taking a set. A hat so made may be rolled or crushed into a small compact mass and may be restored to normal

85 shape uninjured. The article is inexpensive from the standpoints of material and labor cost, is durable, and presents withal an attractive appearance quite inconsistent with its cheapness.

90 While, as hereinbefore set forth, my invention finds its prime application to the employment of paper as a starting material, yet other substances may be employed with measurably satisfactory results if substantially impermeable to air and the strand be made therefrom in tubular form, such for instance as Cellophane.

95 By the term "tubular" is meant a strand which has capacity for the trapping of air therein as distinguished from a flat strip or one tightly twisted into a cord, not necessarily a strand which is of uniform cylindrical section. The characteristic "body" of the strand and the resultant plumpness of the crocheted fabric of my invention may be obtained by a lateral crushing 100 of a strip of material in such manner as to trap

105 110

sufficient air therein to prevent complete collapsing while being worked into the fabric. Also, by the use of the descriptive term "semi-crepe" is meant a paper having similar characteristics of longitudinal elasticity, by whatever trade name designated.

I claim:

1. A homogeneous fabric including longitudinally elastic sealed tubular strands of crushable semi-crepe cellulose material substantially impermeable to air.
- 10 2. An article of manufacture formed of fabric

comprising interlaced twistless tubular strands of soft longitudinally elastic paper.

3. An article of manufacture formed of homogeneous fabric comprising interlaced tubular strands of semi-crepe paper.

4. An article of manufacture formed of homogeneous fabric comprising crocheted tubular strands of semi-crepe paper.

5. An article of manufacture formed of homogeneous fabric comprising interwoven tubular strands of weather-proof semi-crepe paper.

HENRY G. HILLARD.
